US0D1049516S

(12) **United States Design Patent** (10) **Patent No.:** **US D1,049,516 S**
(45) **Date of Patent:** **** Oct. 29, 2024**

(54) **CAT LITTER BOX**

(71) Applicant: **Xiangying Mai**, Hezhou (CN)

(72) Inventor: **Xiangying Mai**, Hezhou (CN)

(**) Term: **15 Years**

(21) Appl. No.: **29/942,750**

(22) Filed: **May 17, 2024**

(51) LOC (14) Cl. **30-11**

(52) U.S. Cl.

USPC **D30/161**

(58) **Field of Classification Search**

USPC D30/108, 109, 114, 115, 117, 118, 119,
D30/120, 161, 162, 199; D6/663, 683;
D3/304, 319

CPC A01K 1/011; A01K 1/033; A01K 1/0107;
A01K 1/0114; A01K 1/0152

(57) **CLAIM**

The ornamental design for a cat litter box, as shown and described.

DESCRIPTION

FIG. 1 is a front perspective view of a cat litter box, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view.

1 Claim, 8 Drawing Sheets
